CLAIM

The ornamental design for a lipstick case, as shown and described.

DESCRIPTION

FIG. 1 is a perspective view of our new design for a lipstick case;

FIG. 2 is a side elevation view of the lipstick case shown in FIG. 1, the opposite side view being a mirror image thereof; FIG. 3 is a top plan view of the lipstick case, shown in FIG. 1;

FIG. 4 is a bottom plan view of the lipstick case, shown in FIG. 1; and,

FIG. 5 is an exploded view of the lipstick case, shown in FIG. 1.

The broken line lipstick bullet illustrates the environment of the lipstick case and forms no part of the claimed design.
